SYNCHRONIZING AND PHASING SYSTEM

George V. Nolde, Berkeley, Calif.

Application May 5, 1943, Serial No. 485,732

8 Claims. (Cl. 172—293)

This invention relates to phasing systems and more particularly to an improved method and control means for phasing the cyclically operable mechanism of transmitting and receiving apparatus in a navigational guide system such as described in the United States Patent Number 2,321,698, issued to George V. Nolde on June 15, 1943, of which this application is a continuation-in-part. It should be understood, however, that although described in connection with a navigational guide system, the method and apparatus disclosed hereinafter may be utilized to synchronize two or more remotely separated cyclic mechanisms of any kind, with respect to speed and cyclic phase of operation.

The present invention represents a development and improvement of an early system used by Hughes in 1855-1863 to synchronize and phase rotating mechanisms of a telegraph printer well known in the art and described in many publications such as, Harrison, "Printing Telegraph Systems and Mechanism," Langman Green and Co., London, 1923, pages 35 to 37. The Hughes system was based on intermittently connecting two remotely separated rotary printing wheels to two separate respective motors by two individual clutches. The two printing wheels were driven through a single revolution and stopped at a given phase of rotation. Preliminary printing signals were transmitted from one station to another at certain prescribed intervals to enable the operator at the receiving station to synchronize his motor with that of the transmitting station. After the motors were thus synchronized the two printing wheels continued to rotate intermittently and the printing signals served to correct the phase of these printing wheels during printing operation proper.

It will be seen from the following detailed description that the present invention represents an improvement of this basic system and provides a fully automatic but relatively simple synchronizing and phasing system as compared with the elaborate modern systems provided for this purpose.

It is a principal object of the invention therefore to provide automatic and positive means for effecting and controlling a continuous and non-interrupted synchronization and phasing of two remotely separated devices.

It is a further object to provide simultaneous phasing of two or more synchronously operable devices.

It is a further object of this invention to provide an improved clutch specifically adapted to

cooperate with alternating current synchronous motors.

It is a further object to provide a positively limited friction slipping mechanism between the driving and driven components of a transmission.

It is a further object to provide a friction slipping mechanism between the driving and driven components of a transmission which will allow the driven component to lag behind the driving component by a predetermined fixed amount.

It is a further object of this invention to provide a phasing system in which a communication channel used for phasing at the beginning of operation is freed thereafter for other signal uses without disrupting phasing.

Other more specific objects will appear during the following description of a preferred form of the invention, reference being had to the accompanying drawing, forming a part of this specification in which:

Fig. 1 is a side elevation of the motor and clutch units of the preferred embodiment of the present invention.

Fig. 2 is a sectional view taken on the line 2—2 of Fig. 1, showing the internal mechanism of the clutch.

Fig. 3 is a sectional view taken on the line 3—3 of Fig. 2 showing method of mounting the clutch pawl to the casing of the clutch.

Fig. 4 is a wiring diagram of the apparatus situated at one location such as aboard an aircraft.

Fig. 5 is a wiring diagram of the apparatus situated at another location such as at a point on the ground.

Fig. 6 is a side elevation of the motor and clutch unit of the modified embodiment showing particularly the slip mechanism between the motor and the clutch.

Fig. 7 is an enlarged view of the spring pressure element of the slip unit.

Fig. 8 is a wiring diagram of the modified embodiment showing particularly the control circuit for the motor, clutch, and slip unit.

45 *Indexed clutches and control mechanism therefor*

The general arrangement of the herein described preferred embodiment of this system is to synchronize two remotely separated motors by a common source of alternating current. One of the motors such as the one on the ground may be synchronized directly to the alternating current in the usual way and the other motor such as the one on board ship or aircraft is synchronized to the frequency of the same source by means in-

cluding a transformer transmitter, receiver, filter, or by any equivalent communication channel.

A clutch is interposed between each motor and the instrument for which it is used. These clutches must be of the kind in which the driven part of each clutch is fixed in a definite angular position relative to the frame of the apparatus when the clutch is disengaged.

The clutches of this general type are widely used in calculating machines, teletypes, et cetera and this type of clutch will be referred to hereinafter as an "indexed clutch."

The indexed clutches used in the present preferred embodiment are engaged by respective electromagnets which are in a common circuit or are controlled through a common communication channel also including transmitting and receiving devices. Simultaneous engagement of the clutches thus causes their respective instruments to rotate at synchronous speeds and in synchronous phases of operation.

The synchronous motor 56 (Fig. 1) which is shown as being for the instrument on board the aircraft, corresponds to the motor of the same number shown in Fig. 4 of the aforementioned Nolde Patent Number 2,321,698. This motor is selectively connected and disconnected to and from the instrument drive shaft 120a by an indexed clutch 60 which may be of the well known ratchet type.

In the particular embodiment shown the ratchet 100 (Fig. 2) has four teeth for reasons set forth hereinafter. This ratchet is fixed to and rotates with the motor shaft 120b. A clutch casing 105 (Figs. 2 and 3) is freely mounted on the shaft 120b and is fixed to the shaft 120a. The casing carries a stud 106 upon which is pivoted a clutch pawl 107 having a tooth 108 adapted to move into engagement with the ratchet 100. A spring urges the pawl clockwise about stud 106 but when the clutch is disengaged, as shown in Fig. 2, such clockwise movement is prevented by a pin 111 blocking a tip 110 of the pawl. Removal of the pin 111 from against the tip 110 by mechanism described immediately hereinafter allows the spring 109 to rock the pawl into engagement with the rotating ratchet whereby the whole clutch as a unit rotates with the ratchet and shaft 120b and thus drives the instrument shaft 120a at the same speed as the motor shaft 120b.

The above described clutch engagement is controlled by an electromagnet 55 (Fig. 1) and related mechanism which includes a conical member 59 which is fixed to the magnet armature and slidably thereby in the bearing 115 in the frame 116 of the apparatus. A pin 58 is journaled in the frame. The right end of this pin engages the member 59 and the left end thereof engages an arm 125 which is integral with a shaft 130 journalled in a bracket or part 126 of the frame 116 (Fig. 1). This shaft carries two arms 127 and 128 which are connected at their outer ends by a square shaft 129, thereby forming a rigid bail comprising the two arms 127 and 128 and the two shafts 129 and 130 all rockable about the center of shaft 130. The upper arm 127 carries an extension which carries the aforementioned pin 111. A spring 132 is compressed between a lug on the frame and a lug on the extension 131 and urges the entire assembly counter-clockwise about the center of shaft 130 and thus normally holds the pin 111 in the clutch disengaging position shown in Fig. 2. Energization of the magnet 55 moves the member 59 upwardly, whereupon the tapered surface of the latter cams

the pin 58 toward the left, as viewed in Figs. 1 and 2, which rocks the arm 125 and shaft 130 clockwise and moves the pin 111 out of the notch in the casing of the clutch to release the pawl 107 and cause engagement of the clutch as described hereinbefore.

Control circuits

The electric motor 36 (Fig. 5) which corresponds to the motor of the same number in Fig. 8 of the aforementioned Nolde patent is connected to a source 150 of alternating current by leads 151 and 152, the latter passing through the transformer 83. This motor is of the well known synchronous type and is therefore driven at a constant speed in synchronism with the frequency of the current source 150.

A transmitter 74, corresponding to the transmitter of the same number in said Nolde patent, is controlled by the secondary winding of the transformer 83 so as to transmit a carrier wave which is modulated by the alternating current of the current source 150. The signal so transmitted is received by a receiver 75 (Fig. 4) which, through a filter, supplies the alternating current of the same frequency as generated by the source 150, thereby causing the motor 56 to rotate in synchronism with the motor 36.

A transmitter 76 (Fig. 4) and receiver 77 (Fig. 5) are also provided and tuned with respect to each other, and when the operator at the receiving station wishes to start operation of an apparatus such as disclosed in said Nolde patent he closes the switches including contacts 148 and 146 (Fig. 4) after having tuned his receiver 75 to the transmitter 74. Closure of the contacts 148 closes the circuit from the battery 156 to the electromagnet 55 described hereinbefore in connection with Fig. 1 which actuates the armature, its cone 59 and pin 58 to cause engagement of the clutch 60. Simultaneous closure of contacts 146 connects the transmitter 76 to the antenna 157 and emits a signal of a prescribed frequency, different from that emitted by the transmitter 74, to an antenna 159 and the receiver 77. An electromagnet 80 is energized by the receiver 77 and closes a switch 147 which closes a circuit between a battery 160 and an electromagnet 47 corresponding to the magnet of the same number in said Nolde patent.

By means of this arrangement, the cone 46 causes engagement of the clutch 44 within a small fraction of a second of the time the cone 59 causes engagement of the clutch 60. It may be observed that with the above described arrangement of the basic parts of such phasing and synchronizing system, any clutch construction may be used, provided both clutches require the same time for engagement and are of the above explained indexed starting type. For cooperation with alternating current synchronous motors, however, certain characteristics of such motors may be used to an advantage in combination with some improved specific features of the clutches, as will be seen from the following description thereof.

In this preferred embodiment the motors 56 and 36 (Figs. 4 and 5) are four pole motors and the ratchets of the clutches 60 and 44 each have four teeth, and therefore, the angular positions of the clutch ratchets are the same at the same instant and simultaneous engagement of the two clutches 60 and 44 will cause the ratchets to drive their housings and respective shafts 120 and 120a from the same starting position at the same

time by the corresponding ratchet tooth of each clutch ratchet. In this way the shafts 120a and 120 are driven at a synchronous speed and in exact phase relation as well, even if the times of operations of the magnets 55 and 47 (Figs. 4 and 5) are slightly different. The number of teeth of the clutch ratchets do not have to be the same as the number of poles of the motors but according to this preferred embodiment may be even multiples thereof such as 4, 8, or 12 teeth for a four pole motor, or 2, 4, 6, 8, etc., for a two pole motor. It is easily understood by those skillful in the art that channels of communication including transmitter 74 and receiver 75 which serves to transmit a synchronizing frequency and the second communication channel including transmitter 76 and receiver 77 which is used to transmit a phasing impulse, may be of any other type besides that described in connection with Figs. 4 and 5 of the present case. For example, a single carrier wave may be used to transmit two modulating frequencies of which one may be used for driving the motors at a synchronous speed and the other for phasing the clutches. Two separate wire lines could be used as well, or any other equivalent means known in the art under the term "communication channels" may be substituted therefor.

Modified embodiment

If the phasing mechanism described above were used to drive a mechanism which had an excessive amount of inertia, the initial load caused by such an instantaneous start as would result from clutch engagement might cause the motor to lose one or more phases of its cycle before the driven part of the apparatus is brought up to the synchronous speed. If this loss of phases were not the same at both stations the system would be out of phase and would therefore not operate correctly, therefore a slipping mechanism may be provided in accordance with the modified embodiment whereby the driven part of the apparatus may initially lag behind the synchronous speed of the motor at each station by a predetermined fixed amount before getting up to speed. This lag could be made any amount from one revolution of motor or ten or twenty revolutions thereof, but in any one case the amounts of slippage or lag must be the same or even multiples of full revolutions for both stations. In the modified embodiment the slippage mechanism permits the clutch and driven part of the apparatus to drop behind the motor by three full revolutions during the acceleration of the clutch following engagement thereof, and after the three revolution displacements to establish a positive driving connection between the motor and clutch.

The motor shaft 170 (Fig. 6) carries integrally therewith a fly wheel 171 to add to the inertia and momentum of the rotating part of the motor. The shaft 170 also has threads 172 on which is threaded a disc 175. The threads on the disc are made to fit the shaft threads with considerable friction and the disc itself is split at 176, as shown in Fig. 7, to permit the disc to spread and prevent binding between the shaft and disc. Preferably the threads on the shaft are slightly larger at the lower end so that the friction between the shaft and disc will increase as the disc is moved downwardly by means described immediately herein-after.

A friction disc 178 is freely mounted on the shaft 170, and supported on that shaft between

the collars 178a and 178b which are pinned or otherwise fixed to the shaft 170. A disc 179 is freely mounted on shaft 170 and is fixed to a coaxial shaft 181. Each of the three discs 175, 178 and 179 has two holes into which are fitted two pins 183 and 184 as shown in Fig. 7. The two pins are fixed to the discs 178 and 179 and are slideable in the holes in disc 175 to permit the latter to slide up and down on the pins.

10 The clutch 60a is of the same construction as clutch 60 described hereinbefore in connection with Fig. 1 and is caused to engage by energization of the magnet 55a and the resulting upward movement of the tapered member 59a in exactly 15 the same way as described hereinbefore.

Before the clutch is engaged, the motor 56a is started by the mechanism shown diagrammatically in Figs. 4 and 5 and described hereinbefore. The clutch ratchet is fixed to shaft 181 (Fig. 6)

20 and is driven by the motor by the above described disc assembly. Since there is a relatively light load required to drive the clutch ratchet idly, the friction between the shaft threads and the threads in disc 175 is sufficient to drive the two 25 discs 178 and 179 and the shaft 181 without slipping. When the clutch is engaged, however, the load is instantaneously increased and tends to retard the disc assembly while the motor speed is maintained, in which event the disc 175 slips on 30 the threads 172 and moves downwardly to the position shown by dotted lines and identified as 175a. When the disc 175 reaches the position shown by dotted lines and identified by the reference numeral 175a, it abuts the collar 178b and is 35 positively stopped, thereby forming a solid and direct connection between the motor shaft 170 and the clutch ratchet shaft 181. The ratchet shaft is thus allowed to drop three full revolutions (in this particular embodiment) behind the motor 40 during the downward travel of the disc 175.

Means must be provided to return the disc 175 to the position shown, therefore, the operation described above is preceded by the following preparatory operation. From the above description

45 it may be seen that during the driving operation of the mechanism the disc is in its lowered position 175a and when the machine is stopped the disc remains in this position. During the above mentioned preparatory operation, before the 50 clutch is engaged, the motor is driven backward. At this same time, an electromagnet 185 is energized which ejects its armature 186 and presses a friction pad 187 against the disc 178 with sufficient force to overcome the friction between the 55 threads 172 of the shaft and those in the disc 175. The disc 175 is thus driven backwards or upwardly to the position shown. The magnet 186 is then deenergized and the motor is reversed and driven forward by means described hereinafter, 60 after which the clutch is engaged and the operation is effected to drive the disc 175 down to its driving position 175a as described hereinbefore.

Alternative wiring diagram

65 An alternative arrangement of the control circuits of the present invention is one in which the power supply and control switches are located at one station which we may call the control station, shown at the bottom of Fig. 8, and initiates operation of mechanism at the remote station shown at the top of Fig. 8. In this system the operator first closes a switch 200 which closes a circuit including lead 201 connected to the source 205 of alternating current, lead 206 through a coil 207, lead 208, the communication channel 209, lead

210, through a second coil 211, lead 212 through the primary winding 213 of a transformer 222, lead 214 to ground. The primary winding 223 of a transformer 224 is also energized by closure of the circuit including lead 229.

Closure of switch 200 also closes a parallel circuit through the synchronous motor 56a (Fig. 8) and a second parallel circuit through a second motor 56b. The first circuit includes lead 215, the closed switch 216, lead 217, through the starting winding of the motor 56a, lead 218 and condenser 219, the contacts 220, lead 221 to ground. The second circuit which leads through the starting winding of motor 56b includes the identical arrangement including leads 225, 226, 227, and 228 to ground. The main winding of the motors 56a is energized by a branch circuit including leads 230 and 231, and their respective closed contacts 232 and 233, while the main winding of motor 56b is similarly energized by leads 234 and 235. With the switches arranged as shown in Fig. 8, the fields of the starting windings of the two motors are such that the motors are driven backwards for reasons described hereinbefore in connection with Fig. 6. Also as described before the brake magnet 185 is energized during the preparatory operation and this is effected by the circuit including lead 215, described above, and lead 237 through the magnet 185, corresponding to the magnet of the same number in Fig. 6, lead 238, switch 239, lead 221 to ground. The break magnet 185a for the remote station is similarly energized by a circuit including leads 240 and 241.

In accordance with the description of Fig. 6 the backward rotation of the motor and energization of the break magnet 185 drives the disc upwardly to the position shown. During the short interval of time required to do this, the coils 207 and 211 (Fig. 8) which are heated coils, heat up 35 their respective bi-metal strips 243 and 244 which move two respective insulation rods 245 and 246 toward the left as viewed in Fig. 8. The leftward movement of rod 245 opens the switch 239 and causes deenergization of the magnet 185 and 40 leftward movement of rod 246 similarly causes deenergization of magnet 185a. Rod 245 also actuates the motor switches so as to open the contacts 216, 232, 233, and 220 and to close the opposing contacts. This reverses the current 45 through the starting windings of motor 56a and temporarily opens and then closes the circuit through the main winding in accordance with the conventional way of reversing a synchronous motor. The rod 246 similarly reverses the motor 56b so that both motors run idly in a forward direction.

All the foregoing operations take only one or 50 two seconds, and so, shortly after closure of switch 200 the operator closes a switch 250 and releases the same which immediately opens again. During the time the latter switch is closed it closes a circuit through the clutch engaging magnet 55a so as to effect engagement of the clutch 60a (Fig. 6). This circuit includes lead 255, connected to a direct current supply unit 256, leads 257, and 258, the normally closed contacts 259, through the clutch magnet 55a, and lead 260 to ground. The clutch magnet 55b for the clutch at the remote station is also energized by closure 55 of switch 250 which closes a circuit including lead 261, the communication channel 265, lead 266, the normally closed contacts 267, through the magnet 55b, lead 268 to ground.

By means of the foregoing arrangement, there-

fore, the motors at both stations are driven backwards during the preparatory operation and the break magnets are energized to drive the disc 175 (Fig. 6) at each station upwardly. Then the break magnets are deenergized and the motors are driven forwardly, immediately after which the clutch magnets 55a and 55b are energized to cause simultaneous engagement of their respective clutches.

Upon such clutch engagement the driven shafts rotate in synchronism and phase and remain in synchronism and phase so long as the clutch magnets are maintained energized. Means are provided to maintain such energization by means of a circuit individual to each station so that communication channel 265 may be freed for other communication. This means is automatically effective immediately upon the initial energization of the clutch engagement magnets as follows. When the cone 59a (Fig. 6) is moved upwardly, as described hereinbefore, to cause engagement of the clutch 60a a collar 270 engages a tip 271 of a lever 272 and rocks the same clockwise about its pivot 273. The lever 272 has an insulation tip 274 which is adapted, upon such clockwise rocking of lever 272, to close a pair of switch contacts 275. An insulation lug 276 is secured to one of the leaves of the latter switch and engages a leaf of the adjacent switch 259 as shown so that following closure of the first switch the lug 276 opens the switch 259 in a manner customary in "make before break" switching arrangements.

The switch 259 at the control station and its corresponding switch 261 at the remote station were described hereinbefore in Fig. 8 as in the circuit which causes initial energization of their respective clutch engaging magnets 55a and 55b. Before these switches are opened, however, the switch 275 is closed as described above, together with the corresponding switch 271 at the remote station and each thus closes a holding circuit through its respective magnet. The closure of switch 275 closes the circuit including lead 288 connected at one end to the D. C. power supply unit 256 and at its other end to one side of the switch 275. The other side of the switch is connected to the magnet 55a which is in turn connected to ground by lead 268. Closure of switch 271 (Fig. 8) at the remote station similarly closes a circuit including lead 281, connected at its upper end to a D. C. power supply unit 282, and at its lower end to one side of the switch 271, the other side of which is connected to the magnet 55b, connected to ground by lead 268. Each magnet is thus maintained energized by means of a circuit and power supply at its own station so that opening of the switches 259 and 261 are ineffective to deenergize the respective magnets.

As described hereinbefore switch 250 is closed by the operator at the control station and then is released to open, and during the short interval of time the latter switch is closed the magnets are energized and their holding circuits are closed so that thereafter the communication channel 265 may be freed for other uses.

The clutches may be disengaged and the entire system including operation of the motors may be stopped simply by opening the switch 200 which opens the circuits through the transformer 224 for the power supply unit 256, the circuit through the motor 56a and the heater coil 207 and through the communication channel 265, the circuit through the heater coil 211 and the transformer 70 75 for the power unit 282 and also the circuits

through the motor 56b. Deenergization of the two power units causes deenergization of the clutch magnets 55a and 55b and disengagement of their respective clutches to thereby bring the system to a condition of rest.

The scope of this invention should not be restricted to the preferred embodiment or modifications described hereinbefore except as limited by the prior art, for example, the ratchet indexed clutches could be replaced by spiral jaw indexed clutches, or any other equivalent construction. The maintenance of engagement of the clutches by the holding circuits disclosed hereinbefore could as well be effected by a mechanical latch; while the solenoids and cone shaped armatures may be replaced by any other well known clutch engaging mechanism. The scope of my invention is described in the following claims.

I claim:

1. A remote control system for synchronizing the phase of rotation of a first device with respect to the phase of rotation of a second device, comprising; a first motor operable to rotate said first device, a second motor operable to rotate said second device, a first clutch between said first motor and said first device, a second clutch between said second motor and said second device, a source of electrical energy, a first communication channel between said source and said two motors for transmitting said energy from said source to said motors to thereby drive said motors at equal speeds, a first electrically controlled means for engaging said first clutch, and a second electrically controlled means for engaging said second clutch, a second communication channel between said first and second clutch engaging means, and means for enabling said second communication channel to simultaneously operate said first and second clutch engaging means.

2. A system for synchronizing and phasing two rotating members having a motor operable to rotate the first one of said two members, a second motor operable to rotate the second one of said two members, a first clutch between said first motor and said first member, a second clutch between said second motor and said second member, a first electrically controlled means for engaging said first clutch, and a second electrically controlled means for engaging said second clutch; in combination with a first communication channel for controlling said motors to rotate at equal speeds, a second communication channel between said first and said second clutch engaging means, and means for enabling said second communication channel to cause simultaneous operation of said first and second clutch engaging means.

3. In a system for synchronizing and phasing a first rotatable member and a second rotatable member, a first alternating current synchronous motor having a predetermined number of poles and operable to rotate said first member, a second alternating current synchronous motor having the same predetermined number of poles and operable to rotate said second member; in combination with two clutches each including an engagement member having a plurality of engagement elements thereon which are equal in number to the number of poles of said motors, the first of said two clutches being interposed between said first motor and said first member, and the second of said two clutches being interposed between said second motor and said second member, and means operable to cause simultaneous engagement of said two clutches.

4. In a system for synchronizing and phasing a first rotatable member and a second rotatable member, a first alternating current synchronous motor having a predetermined number of poles and operable to rotate said first member, a second alternating current synchronous motor having the same predetermined number of poles and operable to rotate said second member; in combination with, two clutches each including an engagement member having a plurality of engagement elements thereon which are equal in number to even multiples of the number of poles of said motors, the first of said two clutches being interposed between said first motor and said first member, and the second of said two clutches being interposed between said second motor and said second member, and means operable to cause simultaneous engagement of said two clutches.
5. In a system for synchronizing and phasing a first rotatable member and a second rotatable member, a first motor operable to rotate said first member, a second motor operable to rotate said second member, and means for controlling said motors to rotate at equal speeds; in combination with two coupling devices each one interposed between its respective motor and rotatable member, said coupling devices including means for causing a predetermined amount of slippage between the motor and its corresponding rotatable member.
6. In a system for synchronizing and phasing a first rotatable member and a second rotatable member, a first motor operable to rotate said first member, and a second motor operable to rotate said second member; a coupling device interposed between one of said motors and its corresponding rotatable member, said coupling device including a friction clutch having a driving member and a driven member, said driving member having a helically threaded portion and said driven member having an element for engagement of said threaded portion.
7. A system for synchronizing and phasing two rotating members having a motor operable to rotate the first one of said two members, a second motor operable to rotate the second one of said two members, a first clutch between said first motor and said first member, a second clutch between said second motor and said second member, a first electrically controlled means for engaging said first clutch, and a second electrically controlled means for engaging said second clutch; in combination with, means for controlling said two motors to rotate at equal speeds, a communication channel between said first and said second clutch engaging means, means for enabling said communication channel to cause simultaneous operation of said first and second clutch engaging means, and means for holding said two clutches in engagement independently of the control exercised by said communication channel.
8. In a system for synchronizing and phasing two rotating members, a motor operable to rotate the first of said two members, a second motor operable to rotate the second one of said two members, a first clutch between the first motor and said first member, and a second clutch between said second motor and said second member; in combination with a communication channel for controlling said two motors to rotate at equal speeds, and means for causing simultaneous engagement of said two clutches.
